UNITED STATES PATENT OFFICE.

CHARLES E. WARNER, OF MELVERN, KANSAS.

WASHING-MACHINE.

SPECIFICATION forming part of Letters Patent No. 398,866, dated March 5, 1889.

Application filed March 22, 1888. Serial No. 268,113. (Model.)

To all whom it may concern:

Be it known that I, CHARLES E. WARNER, a citizen of the United States, residing at Melvern, in the county of Osage and State of Kansas, have invented a new and useful Improvement in Washing-Machines, of which the following is a specification.

My invention relates to improvements in washing-machines; and it consists in certain novel features hereinafter described and claimed.

In the accompanying drawings, Figure 1 is aside elevation of a washing-machine constructed according to my invention. Fig. 2 is a central longitudinal section of the same, and Fig. 3 is a transverse section of the same on the line *x x* of Fig. 1.

Referring to the drawings by letter, A designates the suds-box, preferably of a rectangular configuration, and supported by the legs *a*, as shown. One of the ends of the suds-box is extended vertically, to provide a rail, B, for the attachment of a wringer, as will be readily understood. The top of the suds-box is provided with an opening, C, for the admission of the clothes, and a swinging lid, D, adapted to close the same. The lower corners of the suds-box are cut away, as shown, and on the inner faces of the same I secure the longitudinal ribs E, of inverted-V shape in cross-section. Within the suds-box I provide the beaters or agitators H, projecting upward therefrom, and the cross-bar I, connecting and bracing the said fingers or agitators.

The ends of the main bar or shaft G are provided with angular sockets J, which are engaged by the ends of the set-screws K, and the short shafts L inserted transversely through the upper portions of the legs and the sides of the suds-box, near the lower edges of the same. The set-screws K mesh with interior screw-threads in the openings through which they are placed, and their inner ends engage the sockets in one of the ends of the main bars of the beaters, as clearly shown in Fig. 3. The shafts L are inserted through metallic bushings M, fitted in the openings in the side of the suds-box and in the legs. The inner ends of the shafts are made flat or angular, and engage sockets in the ends of the main bars of the beaters, while their outer ends are provided with the upwardly-extending crank-arms N, connected by a link, O, one

of said crank-arms being somewhat extended and provided with an operating-handle, P. 55 Packing-rings Q are arranged around the shafts L and the inner ends of the bushings M to prevent leakage.

In the operation of the machine the clothes, soap, and water are placed in the suds-box and the lid closed. The beaters are now oscillated by reciprocating the crank-arms, and thereby rotating the shafts L, the motion of the shafts being communicated directly to the beaters, as will be readily understood. As 65 the beaters are oscillated, they will swing to and away from the cut-away portions of the suds-box, and fit between the ribs thereon, thereby thoroughly agitating and beating the clothes. 70

It will be observed that the device is very simple, and that at every stroke of the beaters the clothes will be lifted from the water and thrown forcibly against the ends of the suds-box. By my device the clothes are effectually prevented from clogging in the bottom of the suds-box and can be easily and rapidly cleaned. 75

Having thus described my invention, what I claim, and desire to secure by Letters Patent, 80 is—

1. In a washing-machine, the combination of the suds-box and the beaters arranged within the tub, and consisting of main bars journaled between the sides of the suds-box 85 near the lower edges of the same and fingers projecting upward from the shafts, as set forth.

2. The combination of the suds-box having its lower corners cut away, the longitudinal 90 V-shaped ribs secured to the upper faces of said cut-away portions, the beaters arranged within the suds-box and comprising transverse shafts and fingers projecting upward therefrom and adapted to rest upon the said 95 cut-away portions and between the said ribs, and mechanism for oscillating said beaters, as set forth.

In testimony that I claim the foregoing as my own I have hereto affixed my signature in 100 presence of two witnesses.

CHARLES E. WARNER.

Witnesses:

J. T. PLOWMAN,
J. T. DAVIS.
